UNITED STATES PATENT OFFICE.

ROBERT C. BENDER, OF ST. LOUIS, MISSOURI, ASSIGNOR OF ONE-HALF
TO WILLIAM A. MELETIO, OF ST. LOUIS, MISSOURI.

REFRIGERATOR.

No. 826,466.

Specification of Letters Patent.

Patented July 17, 1906.

Application filed December 5, 1905. Serial No. 290,468.

To all whom it may concern:

Be it known that I, ROBERT C. BENDER, a citizen of the United States, and a resident of St. Louis, Missouri, have invented certain new and useful Improvements in Refrigerators, of which the following is a specification.

This invention relates to improvements in refrigerators; and it consists in the novel arrangement, construction, and combination 10 of parts, as will be fully hereinafter described and claimed.

The object of this invention is to construct a refrigerator consisting of a plurality of receptacles located in compartments of a building and so arranged as to communicate with the various compartments, so that each compartment may be chilled to the desired degree by means of the circulation of the brine from the supply-receptacle to the discharge 20 end of the last compartment.

A further object of this invention is to provide a plurality of compartments, the first having a plurality of ice-receptacles, into which ice and salt are placed, and the drippings from the melted ice circulating through the second compartment and from thence to a third compartment, chilling each compartment by the same supply of ice to a sufficient degree of coldness necessary for 30 refrigerating purposes.

In the drawings, Figure 1 is a perspective view showing the invention or refrigerator-building with a portion of the front wall broken away and in section. Fig. 2 is a 35 vertical sectional view taken on the line 2 2 of Fig. 1. Fig. 3 is a detail cross-sectional view taken on the line 3 3 of Fig. 2. Fig. 4 is a perspective view showing the relative position and arrangement of the receptacles 40 forming my invention.

Referring to the drawings in detail, 5 indicates the dividing-line between the first and second floors of a building, 6 the ground floor, and 7 the second floor.

45 8 and 9 indicate the side walls of the refrigerator, 10 a division-wall, forming two compartments 11 and 12. 13 indicates the top, 14 the bottom, 15 the front wall, and 16 the rear wall, all of said walls forming a complete housing, in which the invention is located.

The walls forming the housing are constructed in any desirable manner to retain the cold air within, such as is generally

known in the construction of refrigerator- 55 boxes.

Under the top 13 and located within the compartment 11 is provided a plurality of receptacles 17, extending from the wall 9 to the division-wall 10 and inclined slightly 60 toward the division-wall 10, and each of said receptacles 17 are provided with a projecting end 18, which extends through openings formed in the division-wall 10 and communicates with the receptacle 19, located within 65 the compartment 12. The receptacle 19 is composed of two end sections 20 and 21 and two side sections 22 and 23. The end section 20 is inclined toward each side section 22 and 23 to discharge the drippings passing 70 from the receptacles 17, dividing the same equally to both sides in order to convey the brine from each of the receptacles 17 into the end section 21 through the agency of the side sections 22 and 23. The end section 21 is 75 provided with an outlet which communicates with a pipe 24, which extends downwardly, passing through the dividing-line 5, and empties the contents of the upper compartments into the pan 25. The pan 25, together with a plurality of like pans 26, are suspended to the ceiling or upper portion of the lower compartment 16, and each are tilted slightly in opposite directions and are connected by pipes 27, connecting each with 80 the other and forming a passage for the ice-water to circulate from one pan into the other in the direction as indicated by the arrows in Fig. 4, and finally discharge the water through the outlet 28 into a trough 29 90 and from thence through the pipe 30, which permits the water to discharge either upon the bottom of the refrigerator into a barrel or into an opening connected with the sewer, as is found preferable in constructing the 95 refrigerator.

The top of the compartment 11 is provided with doors 31, through which the ice and brine are placed into the receptacles 17. The front wall is also provided with doors 32, 100 through which access may be had to the various compartments.

The purpose of extending the trough throughout the length of the lower compartment is that should it be desired to retain the 105 ice-water for any length of time within the trough and to prevent the same from dripping upon the floor then the pipe 30 may be

corked and permit the ice-water to remain within the trough until the same is nearly filled. When such is the case, the pipe may be led into a barrel or some receptacle and the trough may be drained and the water removed without causing the floor to become wet by the continual discharge.

The operation of my invention is as follows: The chipped ice and salt are first placed into the receptacle 17 through the doors 31. The drippings from the melted ice are permitted to pass through the projecting ends 18 and discharge into the end section 20 of the receptacle 19, then permitted to pass in opposite directions to the sides 22 and 23, emptying into the end section 21 and down through the pipe 24 and into the pan 25. From the pan 25 the brine passes into the pan 26 through the pipe 27, and so on the water is circulated from pan to pan, flowing in the direction as indicated by the arrows and finally emptying into the trough 29 through the outlet 28. From the trough 29 the contents is permitted to pass through the pipe 30. It has been found by practical demonstration in the refrigerator now in use that the compartments by means of this circulation are each held to a sufficient degree of coldness to preserve the articles placed therein, and the walls of the various compartments are kept sufficiently dry.

I claim—

1. A refrigerator comprising a plurality of upper compartments, ice-receptacles located within one of the compartments, a receptacle located in a second compartment and receiving the drippings of the receptacles in the

first compartment, a lower compartment, a plurality of pans located within the lower compartment to receive the drippings from the receptacles in the upper compartments and to circulate said drippings from one pan to the other, a trough to receive the drippings from the last pan, said arrangement of receptacles cooling each compartment by one supply of ice, substantially as specified.

2. A refrigerator of the class described having an upper compartment and a lower compartment, a division-wall formed in the upper compartment, doors formed in the top of the upper compartment, a plurality of tilted receptacles located in the top of the upper compartment in which ice and salt is placed, a second receptacle located within the upper compartment between the division-wall and the side wall and communicating with the receptacles located in the upper compartment on the other side of the division-wall, a discharge-pipe extending downwardly from the last-mentioned receptacle through the dividing-line into the lower compartment, a plurality of pans located in the lower compartment and tilted opposite to each other, a pipe connecting said pans one with the other, a trough located beneath said pans, and a discharge-pipe extending from said trough, substantially as specified.

In testimony whereof I have signed my name to this specification in presence of two subscribing witnesses.

ROBERT C. BENDER.
